UNITED STATES PATENT OFFICE.

CHARLES J. LIETZ, OF NEWARK, NEW JERSEY, ASSIGNOR TO IDEAL WRAPPING MACHINE COMPANY, A CORPORATION OF NEW YORK.

RECEIVING AND TRANSFER MECHANISM FOR WRAPPING-MACHINES.

1,384,199.

Specification of Letters Patent. Patented July 12, 1921.

Original application filed March 17, 1917, Serial No. 155,420. Divided and this application filed February 13, 1920. Serial No. 358,480.

To all whom it may concern:

Be it known that I, CHARLES J. LIETZ, a citizen of the United States, and a resident of the city of Newark, in the county of Essex and State of New Jersey, have invented certain new and useful Improvements in a Receiving and Transfer Mechanism for Wrapping-Machines; and I do hereby declare that the following is a full, clear, and 10 exact description of the same, reference being had to the accompanying drawings, and to the numerals of reference marked thereon which form a part of this specification.

This application constitutes a division of 15 my co-pending application for patent for wrapping machine filed March 17, 1917, Serial No. 155,420.

In the wrapping machine forming the subject matter of my application for patent 20 above referred to the wrapped articles (in the present instance caramels) are ejected from a vertical revoluble carrier wheel downwardly against spring-thrust receiving means for holding the wrapped article 25 against the periphery of the wheel and subsequently serve to advance the same toward discharge, causing the wrapped article to pass into and between resiliently acting confining members which hold the folds of the 30 wrapper closely to the article until actual discharge.

It is an object of this invention, therefore, to provide a receiving and transfer mechanism for the wrapped articles which receives 35 the articles directly from the carrier wheel and thereafter effects transfer thereof along a chute toward discharge with a step by step movement. Each additional article discharged from the carrier wheel receives 40 an impulse to thrust the same into the chute and thereby effect movement of all of the articles therein.

Other and further important objects of 45 this invention will be apparent from the disclosures in the drawings and specification.

The invention (in a preferred form) is illustrated in the drawings and hereinafter more fully described.

Drawings.

Figure 1 is a fragmentary front elevation with parts omitted of the receiving and

transfer mechanism at the moment of reception of an article thereon.

Fig. 2 is a similar view with the parts 55 in another position of adjustment.

Fig. 3 is an enlarged vertical section with parts in elevation taken longitudinally through the transfer chute.

Fig. 4 is an interior plan view thereof with 60 parts broken away and shown in section.

Fig. 5 is a plan view of the parts shown in Fig. 2 with parts broken away and shown in section.

Fig. 6 is an interior view of the discharge 65 chute shown in Fig. 7 with parts omitted.

Fig. 7 is a detail section on line 7—7 of Fig. 5.

Fig. 8 is a fragmentary view with parts 70 broken away and shown in section of a portion of the mechanisms of Fig. 1.

Description.

The frame structure of the wrapping machine shown fragmentarily in Fig. 5 is indicated as a whole by the reference numeral 75 1 and the front plate attached thereto shown in Figs. 1, 2 and 5 and forming part of the frame is denoted by the reference numeral 2. Journaled within a boss 3 on the 80 plate 2 is a shaft 4 provided with a gear 5 on its inner end driven by a gear 6 forming a part of the power mechanism of the wrapping machine. On the other end of the shaft 4 a crank 7 is secured to rotate with 85 said shaft, and has connected thereto a link 8. Said link 8 is pivotally connected to the upper end of a crank 9 which is journaled upon a casing 10 secured over the frame plate 2. Pivoted adjacent to said crank 9 90 is another lever or crank 11 and said levers are connected to one another at their upper ends by a link 12 which is operated thereby. The forward end of said link 12 is formed with a pusher plate or ejecting head 13 and 95 said head extends outwardly on each side of and is adapted to slide upon the upper surface of two similar levers 14 during certain portions of its movement. The arms or levers 14 are in reality the extended ends of a 100 forked lever, that is, they are integrally connected with one another at their point of pivotal connection as clearly shown in Fig. 5 and are mounted upon a pintle 15. Said

pintle shaft 15 is supported in bearing blocks 16 which are integral with one another and attached upon a portion of the casing 10 by screw bolts 17 shown in Fig. 5. Each of 5 said levers 14 has a straight flat portion 18 and at the end thereof is cut away to form a tooth 19, as shown in Figs. 3 and 7. Said forked levers 14 are normally supported and thrust upwardly by a coiled spring 20 which 10 as shown in Fig. 7 rests upon a stud 21 on the top casing 10 and engages around another stud 22 on the under side of the forked levers 14. Said spring 20 acts to hold said levers 14 upwardly in pressure relation against the under side of the carrier wheel 23 by which the articles 24 are carried during the application of a wrapper thereon. A bracket 25 shown in Figs. 1 and 15 2 is attached by means of a stud 26 upon the frame plate 2 and rigidly secured upon 20 said bracket is a channel-shaped guide 27 the side walls of which extend beyond the end thereof and are flared outwardly as denoted by the reference numeral 28 and shown in Fig. 4. At its other end said side walls extend beyond the bottom thereof as shown in Fig. 3 and secured on the bottom of said channel 27 at the discharge end thereof by means of a rivet 29 or other suitable means 25 is a false bottom 30 which, as shown in Fig. 3, due to its inherent resiliency is normally sprung upwardly and at its free end is provided with a tooth extension 31 adapted to be engaged by the toothed ends 19 of the 30 levers 14 when the same are forced downwardly by an article 24 received from the wheel 23 into the relation shown in Fig. 8 so that the flat portions 18 of the levers 14 are flush with said false bottom 30. A stud 35 32 secured upon the front of the wrapping machine structure projects outwardly therefrom and has attached thereon a long, resilient confining bar 33 which is normally impelled toward the false bottom 30, and a series of articles 24 leaving the machine are 40 forced therealong in the channel 27 and held tightly between said bar 33 and the false bottom 30 so as to fix the creases in the folds of the wrapper on the articles.

50

Operation.

When an article has had its wrapper completely folded thereon while in the carrier wheel 23 and is ejected from the carrier 55 pocket in said wheel, it is first forced against the forked levers 14, as it leaves the carrier wheel, which are pressed downwardly against the compression of the spring 20 thereby preventing accidental displacement 60 of the article during its ejection from the wheel. As the carrier wheel continues its movement, the smooth periphery thereof beyond the pocket bears upon the top surface of the article 24, as shown in Figs. 1 and 65 8, thereby holding the arms 14 downwardly.

The next operation to take place before another article is discharged is transfer of the article into the chute or channel 27 by the pusher plate or head 13. The operation of the respective cranks 9 and 11 carrying 70 the link 12 on which the pusher head 13 is mounted is timed so that the pusher head is impelled forwardly against the article 24 striking the same and moving the article along on the levers 14 from the position in Fig. 1 to a position within the chute on the false bottom 30 shown in Figs. 2 and 3. Immediately thereafter the pusher head 13 is retracted by return movement of the link or bar 12, and retraction of the pusher head 80 13 from over the flat portions 18 of the levers 14 permits said levers to be impelled upwardly again into contact with the periphery of the carrier wheel 23. As succeeding articles 24 are discharged from the 85 carrier wheel and thrust into the discharge chute on channel 27, to form a series as shown in Fig. 3, the entire series is given an intermittent advance by the addition from time to time of an article ejected from 90 the carrier wheel. As said articles, as shown in Fig. 3, pass through the discharge chute beneath the resilient bar 33 and supported by the resilient false bottom 30, the folds in the wrapper are creased, and since the final 95 folds of the wrapper are on the top surface of an article in the discharge chute, the creasing thereof insures retaining of the wrapper upon the article.

I am aware that numerous details of construction may be varied through a wide range without departing from the principles of this invention, and I therefore do not purpose limiting the patent granted otherwise than necessitated by the prior art.

Claims.

1. In a wrapping machine the combination with a wrapping wheel, of receiving means to receive the wrapped article ejected from the wheel, said receiving means holding the article thrust against the periphery of said wheel after discharge therefrom, a discharge chute, a top wall portion thereof fitted close to the periphery of the wheel, and ejecting means to eject the wrapped article along said receiving means beneath said wheel and beneath the top portion of said chute and into said chute.

2. In a machine of the class described receiving means to receive the article discharged, a discharge chute to receive the article from said receiving means, said discharge chute comprising side walls, a resilient bottom movable with said receiving means, and a spring top whereby the articles are confined within said chute and the folds of the wrapper ironed down.

3. In a wrapping machine of the class described a wrapping wheel, receiving means

- to receive the discharged article from the wheel, a discharge chute, said receiving means normally impelled toward said wheel to hold the article against said wheel after discharge therefrom, and ejecting means associated with said receiving means to eject a wrapped article from beneath and out of contact with the wheel into said discharge chute, said discharge chute provided with a 5 resilient top wall to hold the article closely therewith and iron the folds of the wrapper thereon.
4. In a wrapping machine rotative carrying means for an article, a receiving means 10 for the wrapped article, adapted to be moved by ejection of an article thereon from said carrying means, and ejecting mechanism for thrusting the wrapped article from said receiving means.
5. The combination with a wrapping machine and its wrapping wheel of receiving means normally in contact with the wheel to receive an article discharged thereto and movable away from said wheel with the article, said receiving means holding the article in contact with the wheel and ejecting mechanism to move said article from the receiving means.
6. In a wrapping machine the combination 20 with the wrapping means of receiving means in contact therewith to receive an article thereon and movable away from said wrapping means with said article, and means operating said receiving means to hold the article against the wrapping means.
7. In a wrapping machine the combination 25 with the wrapping means of receiving means in contact therewith to receive an article thereon and movable away from said wrapping means with said article, means operating said receiving means to hold the article against the wrapping means and ejecting mechanism to remove the article from said receiving means.
8. In a wrapping machine the combination 30 with the wrapping wheel of yieldably mounted receiving means in contact there-
- with and movable therefrom by discharge of an article thereto, a receiving chute, resilient means therein on which the articles are supported, and coacting devices between said resilient means and said receiving means whereby the former is moved by the latter prior to the transfer of an article from the latter to the former.
9. In a device of the class described a discharge chute having a lower yieldably mounted plate therein, an upper yieldably mounted plate and a receiving mechanism in cooperative relation with said lower yieldable plate.
10. In a device of the class described, the combination with a candy wrapping wheel of a candy receiving device at the lowermost point of said wheel, a discharge chute having a lower spring plate urged upwardly at its forward part, and an upper spring plate urged downwardly at its rear part, and means to align said receiving device with said lower plate.
11. In a device of the class described, the combination with a candy wrapping wheel of means to receive the wrapped candy ejected from said wheel, a discharge chute having a yieldable bottom plate against which said means is adapted to abut and a device for shoving said candy into said chute.
12. In a wrapping machine, yieldable receiving means to receive an article and movable with the article, a chute having a lower spring plate normally urged upwardly adapted for alinement with said means and an upper spring plate normally urged downwardly and co-operating with said lower plate to fix the creases in the folds of a wrapped article.
- In testimony whereof I have hereunto subscribed my name in the presence of two subscribing witnesses.
